INITIAL HOLDER

Oscar F. Placco, Cranston, R. I., assignor to Coro-
Gram, Inc., New York, N. Y., a corporation of
New York

Application January 29, 1938, Serial No. 187,601

3 Claims. (Cl. 40—142)

My invention relates to a new and improved initial holder.

One of the objects of my invention is to provide an improved initial holder which can be used in connection with, or as part of, a buckle or brooch or other ornamental article.

While the invention relates particularly to a device in which one or more initials are held within a suitable frame, it is to be understood that ornamental articles other than initials can be utilized without departing from the invention.

Other objects of the invention are to provide a device which can be manufactured simply and at low cost and which can be readily assembled and taken apart.

Other objects of my invention will be set forth in the following description and drawing which illustrates preferred embodiments thereof, it being understood that the above statement of the objects of my invention is intended generally to explain the same without limiting it in any manner.

Fig. 1 is a rear elevation of the invention.

Figs. 2, 3 and 4 are respectively sectional views on the lines 2—2, 3—3 and 4—4 of Fig. 1.

Fig. 5 is an enlarged perspective detail view showing a corner of the holding frame.

The embodiment illustrated in Figs. 1—5 comprises a front frame 1 which may be of any suitable design. The front face of said frame 1 can be ornamented in any desired manner. Said frame 1 is provided with an opening having side edge-walls 2 and top and bottom edge-walls 3. The rear wall of the frame 1 is formed so as to provide spaced teeth of rectangular or other shape, having intermediate recesses. Said frame 1 can be made from a single piece of metal or other suitable material and the teeth 4 and the intermediate recesses can be formed by suitably shaping said piece of metal. Rigid knobs 5 project rearwardly from the rear face of the frame 1. Four of these knobs are preferably provided, one of said knobs being located at each corner of the opening in the frame 1.

The initials 6 may be of the general shape shown in Fig. 11. Said initials are provided with lugs 6a. Said lugs 6a may be thinner than the initials 6. The rear surfaces of said lugs 6a may be flush with the rear surfaces of the initials 6.

Each initial 6 may be provided with one or more longitudinal lugs 6a at each end thereof. Said lugs 6a fit into the recesses between the longitudinal teeth 4, so that the front faces of the initials are flush with the front face of the frame 1, when the initials are assembled with the frame.

Figs. 2 and 3 show that the front surface of the frame 1 and the front surfaces of said initials 6 are decorated with jewels J.

Fig. 1 shows the top and bottom faces of the teeth 4 flush with the top and bottom edges 3. This may be varied without departing from the invention and the teeth 4 may be shorter than as illustrated in Fig. 1, so that the top and bottom edges of the teeth 4 are spaced from the top and bottom edges 3.

When the initials are assembled with the frame, the assemblage is loose, so that the initials can fall out of the frame. The lugs 6a and the teeth 4 merely serve to position the initials and to limit the lateral movements of the initials relative to the frame.

The initials are held in position by means of a holding frame 7 which is made of metal or the like. This frame is generally of rigid construction, although it may be somewhat bendable or springy.

As shown in Fig. 5, the inner walls of said frame are cut away at the corners so as to provide inner corner slots 8, openings 9, and longitudinal and lateral slots 10 and 11, which have respective enlargements 10a and 11a.

As shown in Fig. 3, the members 5 may be of rivet-like construction. In Fig. 1 a part of the frame 7 is omitted so as to illustrate the parts more clearly. Fig. 1 shows how the heads of the members 5 can be caused to register with the openings 9, and said frame 7 can then be pushed towards the rear of the frame 1 until the reduced necks of said members 5 are located within said openings 9.

Hence, although the frame 7 can be of substantial stiffness so that it does not bend under ordinary handling, a snap-fastener connection is provided whereby the initials 6 are firmly held in position, with their front faces substantially flush with the front face of the frame 1.

The frame 7 can be readily removed, since the springy connection at its corners is releasable.

The holding frame is sufficiently rigid so that it can be applied or removed repeatedly, without substantially distorting the same.

I have shown a preferred embodiment of the invention, but it is clear that numerous changes and omissions can be made without departing from its spirit.

The holding frame is preferably more resilient and yieldable than the holding means which hold said holding frame in position. In Fig. 1, said holding means are the members 5.

Whenever I refer to initials in the description

of claims, I include identifying or ornamental members of any kind.

I claim:

1. A first frame having an opening in which initials are located, said first frame having first holding means located at its rear face, a holding frame shaped to overlie the rear walls of said initials and to hold said initials in position in the first frame, said holding frame being bodily 10 and wholly removable from the first frame by movement in a direction substantially perpendicular to said first frame, said holding frame having additional holding means, said first holding means and said additional holding means being shaped to interlock resiliently and releasably 15 when the holding frame is moved towards the first frame in a direction perpendicular to the first frame.
2. A first frame having an opening in which initials are located, said first frame having holding means at its inner face, a holding frame shaped to overlie the rear walls of said initials and to hold them in position in the first frame, the holding means of said first frame interlocking 20 releasably with said holding frame, said holding means of the first frame being rearwardly extending members having shanks which terminate in enlarged heads, said holding frame having per-

forated and slotted resilient portions which resiliently engage said shanks inwardly of said heads, said shanks being located in the perforations of said resilient portions, said heads extending rearwardly of said holding frame.

3. A first frame having an opening in which initials are located, holding members connected to said first frame and projecting rearwardly from the rear face of said frame, said holding members having shanks which terminate in enlarged heads, a holding frame shaped to overlie the rear walls of said initials and to hold them in position, said holding frame having perforations at its corners, said holding frame having its walls at each corner provided with slots which form continuations of said perforations, said slots being located between the outer and inner edges of said walls, said walls of the holding frame having additional slots at their corners which also form continuations of said perforations and which interrupt the inner edges of said walls, the corners of said frames being resilient, said perforations being shaped to fit substantially around said shanks, so that said holding frame can be sprung into holding position by forcing said heads through 25 said perforations.

OSCAR F. PLACCO.
